Vogue Tyre Advertisement—date unknown.

Primary Examiner—James Gandy*Assistant Examiner*—Robert M. Spear*Attorney, Agent, or Firm*—R. Reams Goodloe, Jr.[57] **CLAIM**

The ornamental design for a surface pattern for a tire sidewall, as shown and described.

DESCRIPTION

FIG. 1 is a perspective view of a surface pattern for a tire sidewall, showing my novel design; and,

FIG. 2 is a side elevational view of a surface pattern for a tire sidewall tire, showing my novel design.

The figures are lined to indicate the color gold.

The broken line showings of a tire and lettering are for illustrative purposes only and form no part of the claimed design.
